UNITED STATES PATENT OFFICE

JOHN ELLIOTT JENKINS AND SAMUEL E. ADAIR, OF CHICAGO, ILLINOIS, ASSIGNEES TO
JENKINS & ADAIR, INC., OF CHICAGO, ILLINOIS, A CORPORATION OF ILLINOIS

CONDENSER TRANSMITTER APPARATUS

Application filed July 30, 1928. Serial No. 296,252.

Our invention relates to transmitter apparatus and particularly to apparatus for use in connection with sound pick-up devices of the condenser type used for broadcasting purposes.

In using condenser type transmitters and instruments of like nature, it is desirable to have the electrical conductors extending between the transmitter and the amplifier as short as possible in order to increase the operating efficiency of the transmitter and to this end, the present invention provides a durable, practical and conveniently arranged device for supporting a transmitter, said device being designed to support a transmitter in juxtaposition with respect to an amplifying unit, whereby the length of the connecting leads or conductors will be reduced to a minimum.

It is also an object of our invention to provide a transmitter device of the instant nature which comprises a very compactly arranged amplifying unit which is self contained and readily accessible or removable for purposes of repair or replacement, from a suitable housing without disturbing the position of a sound pick-up unit or transmitter supported by said housing.

A still further object of the present invention is to provide a support which includes a frame or casing for resiliently supporting a transmitter and a resilient clamping band in which the transmitter may be detachably supported, this clamping band serving as a very convenient means to permit the association or disassociation of the transmitter without requiring the dismantling of any of the supporting elements.

Our invention further contemplates the provision of a transmitter support which includes a plurality of radially positioned non-metallic resilient members, said members being secured to a mounting at their outer extremities, the inner extremities thereof being associated with the transmitter unit, said members being of such a construction as to prevent the introduction of interfering, humming noises which have heretofore been occasioned when metallic springs and the like

have been employed to support the usual carbon type transmitters.

In addition to the above mentioned advantageous characteristics, our invention contemplates the provision of an economical and durable condenser transmitter supporting device in which the effectiveness of the output is greatly enhanced by reason of the fact that the shortness of the leads which connect the transmitter and the amplifier reduces the inactive capacity to a minimum, and conductors which are adapted to be connected to the output and battery terminals, are compactly arranged so as to present a flexible cable, said conductors being provided with a metallic sheathing which serves as a shield against the introduction of noises resulting from external influences to which the cable may be subjected.

A still further object of this invention is to provide an amplifier casing of rigid construction and pleasing appearance which is designed to support a transmitter and which is further adapted for convenient attachment to conventional types of microphone stands, said casing being also designed to rest upon a flat surface in instances where microphone stands can not be conveniently used.

Another and more specific object of our invention is to provide a condenser transmitter for broadcasting, phonograph recording and other power speaking systems which comprises an amplifier housing and transmitter support of attractive design and adapted for convenient association with conventional microphone stands, said housing having an open back portion which exposes the elements comprising the amplifier when a housing cover is removed, thereby greatly facilitating the repairing or replacement of said amplifier elements.

These and other objects will be more apparent from the following detailed description when considered in connection with the accompanying drawings wherein:

Figure 1 is a front elevational view of a transmitter device which is representative of one embodiment of our invention, said device being shown in association with a microphone stand of conventional design;

Figure 2 is a side elevational view of the device shown in Figure 1;

Figure 3 is a rear view of the transmitter device as viewed along the line 3—3 of Figure 2;

Figure 4 is a vertical central sectional view taken substantially on the line 4—4 of Figure 3, certain of the elements such as the vacuum tube and the transmitter proper being shown in elevation;

Figure 5 is a detailed front elevational view of the improved transmitter clamping ring;

Figure 6 is a fragmentary view of the improved cable which is provided with metallic sheathing for electrically shielding the conductors which comprise said cable; and

Figure 7 is an enlarged transverse sectional view of the cable taken along the line 7—7 of Figure 6.

Referring now to the drawings wherein like numerals have been employed to designate similar parts throughout the various figures, it will be observed that one embodiment of our invention resides in a casing or frame member 2 of box-like design which is adapted to be open at the back thereof by the removal of a cover member 4. This cover member 4 is removably secured to the casing by means of suitable thumb screws 6. The casing 2 and the cover 4 serve to effectively house or enclose a compactly arranged amplifying unit indicated generally by the numeral 8, Figures 3 and 4 and the elements 35 constituting this amplifying unit such as the vacuum tube 10, the terminal supporting bar 12 and other elements which need not be specifically set forth, are self-contained within a rectangular frame 14. This frame 14 provides a convenient mounting for the amplifier parts and is resiliently secured or floated within the casing by means of pads 16 constructed of sponge rubber or material having similar resilient characteristics, said pads 45 being interposed between the casing walls and the frame 14. These pads are preferably cemented to the inner surfaces of the casing walls and permit the amplifying unit 8 contained within the frame 14 to be readily withdrawn from the casing when the cover 50 4 has been removed.

Extending outwardly from the front side of the casing 2 are four equally spaced support arms 18, the outer extremities of which 55 are provided with suitable screws 20. These screws 20 are designed to receive one of the extremities of resilient non-metallic members 22, the opposite extremities of said resilient members being connected to eye hooks 60 24 mounted upon the peripheral surface of a split clamping ring 26. This resilient clamping ring 26 is adapted to receive a microphone unit 28 of the condenser type and a non-metallic resilient member 30, Figure 1, extending between adjacent eye hooks

24 across the split portion of said ring, cooperates with the inherent resiliency of the ring to cause the microphone 28 to be securely clamped in position. It will be observed that by employing our simple split 70 ring structure the transmitter unit 28 may be expeditiously associated with and disassociated from the resilient supporting members 22 without necessitating the dismantling or rearrangement of the members 22. This 75 is to be clearly distinguished from microphone supporting devices which have heretofore been employed wherein considerable time and effort must be expended in order to remove or replace the microphone or 80 transmitter unit. In this connection it is also to be understood that we prefer to employ non-metallic resilient supporting members such as members 22 in order to positively preclude the introduction of undesirable 85 humming or singing noises which are occasioned when metallic structure such as coil springs and the like are used as a supporting medium. The lower portion of the clamping ring 28 is provided with a socket 90 32, Figures 2, 4 and 5 which is designed to slidably receive a companion terminal plug 34 which forms the terminal of a ground wire 36. The transmitter 28 is electrically connected with the amplifier unit 28 through 95 the medium of a conductor 38 which is provided with a plug 40, Figure 4, at one terminal thereof, said terminal being designed for removable insertion centrally of the transmitter 28. The opposite extremity of 100 the conductor 38 is suitably connected to the operative circuit of the amplifier unit and likewise the opposite terminal of the ground wire 36 is connected to a suitable binding post 42, Figure 3, mounted upon the lower 105 side of the frame 14. From the foregoing it will be apparent that the plug and socket arrangement just described, together with the resilient clamping ring 26, renders the amplifying unit 8 readily removable from the casing 2 without the necessity of disturbing the position of the transmitter unit or any of the supporting elements associated therewith. Likewise the transmitter unit may be readily removed from the resilient clamping ring 26 110 and disconnected from the ground wire 36 and the conductor 38 with little effort and without necessitating the rearrangement of any of the transmitter parts. By having the condenser transmitter 28 juxtaposed 115 with respect to the amplifier unit 8, the connecting leads, namely the ground wire 36 and the conductor 38, will obviously be very short. By having these wires of minimum length, the effective variation in capacity of 120 the condenser at voice frequencies is obtained and by employing a transmitter of our construction the output resistance is reduced to a minimum.

It will be observed that the terminal sup- 130

porting bar 12 is vertically positioned within the frame 14 and is designed to support a plurality of terminals or binding posts for the conductors which comprise a cable 44. 5 Three of these binding posts may be connected to battery through suitable conductors 46, 48 and 50, Figures 3, 6 and 7, and the other two binding posts may be connected with out-put conductors 52 and 54. In order to 10 prevent the introduction of noises which might result from conditions surrounding the conductors, we apply a metallic sheathing 56 upon the output conductors 52 and 54 and another metallic sheathing 58 around 15 the entire group of conductors, as clearly shown in Figures 6 and 7 which contacts with the shield or sheathing 56 throughout its entire length. An insulating fabric covering 60 is applied to the outer surface of the metallic sheathing 58.

It will be observed that the sheathings 56 and 58 are preferably braided, thereby rendering the cable sufficiently flexible to meet the needs incident to its use. By having the 25 conductors shielded by these metallic sheathings in the manner shown, the operating efficiency of the described apparatus is materially increased by reason of the fact that the quiet operation thereof is insured. In 30 other words, external disturbing influences to which the cable may be subjected are rendered ineffective by reason of the shield 58 and the shield 56 protects the output conductors against disturbing effects of the current flow within the battery conductors. It 35 will be observed that the cable 44 passes through an insulating collar 62 which is mounted within the bottom wall of the casing 2, and this collar has a sliding fit within 40 a groove in the casing, thereby rendering the collar readily removable after the cover 4 has been removed. In order to properly connect the metallic sheathing 56 and 58 to ground, an extended portion of the sheathing 45 56, Figure 3, is provided which is suitably connected to the ground terminal or binding post 42. In order to effectively connect the metallic frame 14 to ground, a resilient contact finger 66, Figure 3, is secured 50 to the side of the frame 14 and is adapted to resiliently engage the inner surface of the casing 2. It will also be apparent that contact between the sheathing 56 and 58 may 55 be effected other than by making contact throughout the entire length thereof.

The entire transmitter device is adapted for attachment to a conventional type of microphone stand indicated generally by the numeral 68. This stand 68 includes an upright 60 stem or rod 70 which is designed to detachably receive a ring type supporting member 72. A plurality of eye hooks 74 equally spaced along the inner periphery of the ring member 72 are adapted to be clamped against 65 projections 76, Figures 2 and 4, which ex-

tend outwardly and are formed integral with the casing 2. Convenient means such as thumb screws 78 may be employed to clamp these eye hooks 74 against the projections 76. The transmitter device is thus adapted 70 to be conveniently mounted and well balanced at the upper extremity of the microphone stand and in instances where it is not convenient to employ an upright microphone stand, supporting members or feet 80 formed 75 at the lower portion of the casing 2 provide convenient means to enable the transmitter device to be placed upon a flat surface such as a desk or table.

From the foregoing description it will be 80 understood that our invention provides a portable transmitter device which is not only ornamental in appearance, but which is also of a very practical construction. By having the condenser transmitter unit juxtaposed 85 positioned with respect to the amplifier unit, the length of the connecting conductors is reduced to a minimum and by having said amplifier unit self-contained within a frame, and detachably mounted within a casing, the 90 ease with which replacement, repairs and the like may be made is greatly facilitated. It is also to be understood that the non-metallic resilient members which support the microphone unit will not cause any noises to be introduced 95 within the microphone in response to the jarring or inadvertent displacement thereof. As already suggested, this construction should be distinguished from the use of metallic supports which might introduce 100 noises in response to the springing or flexing thereof. By employing our improved annular clamping device for securing the transmitter unit in position, said unit may be removed or inserted without the necessity of 105 rearranging or disassembling any of the transmitter supporting elements. It will further be appreciated that an advantageous 110 characteristic of a transmitter device produced in accordance with the teachings of our invention resides in the use of shielded conductors which are connected with the amplifier unit. The metallic braided sheathing material included within the flexible cable serves very effectively to eliminate the introduction of disturbing noises, which might otherwise be introduced as the result of conditions surrounding said conductors. In addition to the above mentioned desirable characteristics, it will be readily understood that 115 our improved condenser transmitter device may be conveniently mounted upon a conventional microphone stand and is also designed to be placed upon a flat surface such as a desk or table top in instances where it is more advantageous to have the device thus positioned. By having the open back arrangement of the transmitter casing, the accessibility to the various parts which constitute the amplifier unit is greatly facilitated and by having the 120 125 130

plug and socket connection between the amplifier leads and the microphone unit, said amplifier may be removed from the casing without the necessity of changing the position of the microphone. Thus our invention contemplates the provision of a transmitter device which is durable in construction, conveniently mountable, efficiently operable and pleasingly ornamental in design.

10 By the word "frame" as used herein we mean any type of support or carrier for one or more amplifier elements such as vacuum tubes, whereby access may be readily had to amplifier elements, and whereby one or more of said elements may be conveniently removed from or associated with the housing.

Having thus described our invention, what we claim as new and desire to secure by Letters Patent is:

20 1. In transmitter apparatus of the class described, a frame for supporting a condenser type transmitter, a unitary amplifier supporting means adapted to be detachably associated with the frame in juxtaposition with respect to a supported transmitter without the necessity of disturbing the position of said transmitter and a complete amplifier unit on said supporting means.

30 2. In transmitter apparatus of the class described, a frame, a resilient clamping ring adapted to yieldingly engage the surface of a transmitter unit and means carried by the frame for properly supporting the clamping ring.

35 3. In combination with an amplifier unit having relatively short leads adapted to make a sliding contact with condenser type transmitter, a frame adapted to render the amplifier unit substantially self contained, a housing for said frame having an open back portion to permit of the convenient association and disassociation of the frame with respect to the housing, and means carried by the housing for supporting a transmitter in juxtaposition with respect to the housed amplifier unit.

40 4. In transmitter apparatus of the class described, a frame for supporting an amplifier unit, means for supporting a condenser transmitter adjacent to a supported amplifying unit, and a plurality of adjacently positioned output and battery electrical conductors extending from the amplifier frame having metallic sheathing for electrically shielding the individual adjacently positioned conductors.

45 5. In combination with an amplifier unit and an adjacently positioned transmitter connected thereto, a plurality of compactly arranged battery and output conductors, and a metallic sheathing enclosing and separating certain of said conductors to protect against the introduction of sound disturbances.

60 6. In combination with an amplifier unit

and an adjacently positioned transmitter connected therewith, a plurality of compactly arranged battery and output conductors, braided metallic sheathing surrounding said conductors to electrically protect against the introduction of disturbing sounds from external influences, and a metallic sheathing within said first mentioned sheathing and surrounding the output conductors.

7. In combination with an amplifier unit 75 and an adjacently connected transmitter, a plurality of compactly arranged battery and output electrical conductors, a flexible metallic sheathing surrounding the output conductors to electrically protect against disturbing effects from the current flow within the battery conductors, and another flexible metallic sheathing surrounding the battery conductors and having contact with the first mentioned sheathing to further protect the 80 conductors as a shield against the introduction of sound disturbances from external influences.

8. In transmitter apparatus of the class described, a frame for supporting an amplifier unit, a housing therefor, said housing being designed to support a transmitter unit, and means provided on said housing for securing the same to an upright elongated transmitter stand, said housing being also designed to be 95 positioned upon a flat surface, in lieu of the association thereof with an upright transmitter stand.

9. In transmitter apparatus of the class described, a frame for supporting an amplifier unit, a housing for detachably receiving the amplifier unit supported by the frame, a removable cover at the back portion of the housing, means on the front portion of the housing for supporting a transmitter unit, and means for securing the housing to the 100 top of an upright stand.

10. In a transmitter apparatus of the class described, a frame for compactly supporting a complete amplifier unit, a box-like housing adapted to detachably receive said amplifier frame, a substantially complete amplifier unit in said frame, resilient means interposed between the inner surface of the box-like housing and the outer surface of the frame 115 for properly mounting said frame within the housing, means for supporting a transmitter upon the housing in juxtaposition with respect to a supported amplifier unit, and a removable cover member on said housing which is adapted when removed to expose all of the elements comprising the supported amplifier unit, thereby greatly facilitating the ease with which replacement or repairs may be made.

11. In transmitter apparatus of the class described, a housing, a frame detachably mounted within said housing, a substantially complete amplifying unit including a vacuum tube, transformer, condenser and 120 con-

ductors housed within said frame and movable therewith as a unit, whereby said complete amplifier unit may be readily attached or detached with respect to said housing, and a transmitter unit supported by said housing in juxtaposition with respect to the housed amplifier unit.

12. In transmitter apparatus of the class described, a housing, a frame having side walls and an open end portion, said frame being detachably mounted within said housing, a substantially complete amplifier unit including a vacuum tube, transformer, condenser and conductors mounted within the walls of said frame, whereby said amplifier unit may be moved with the frame as a self-contained unit, a cover on said housing adapted when open, to expose the open portion of the amplifier supporting frame and thereby render the amplifier elements readily accessible, and a transmitter unit supported by said housing in juxtaposition with respect to said amplifier unit.

13. In transmitter apparatus of the class described, a frame, an annular member having a smooth inner surface, a cylindrical transmitter unit having a smooth peripheral surface adapted to make a sliding fit within said annular member whereby said parts may be connected by imparting relative axial movement thereto, and supporting means extending between the frame and the annular member.

14. In transmitter apparatus of the class described, a frame, said frame having an internal annular surface associated therewith for slidably receiving a cylindrical transmitter unit, and a transmitter unit having a cylindrical surface adapted to make a sliding fit with said internal annular surface, whereby said parts may be connected by imparting relative axial and rotative movement thereto.

15. In transmitter apparatus of the class described, a housing, a detachable frame within said housing, an amplifier unit mounted in said frame, a condenser transmitter unit supported by said housing and positioned adjacent said amplifier unit, and means for electrically connecting said condenser transmitter unit and said amplifier unit, said connection being such as to enable the disconnection of the transmitter unit from the amplifier unit by manually urging said condenser transmitter unit away from said amplifier unit.

16. In transmitter apparatus of the class described, a housing, a frame detachably mounted within said housing, an amplifier unit within said frame, a cylindrical condenser transmitter unit detachably supported by said housing, said transmitter unit having a cylindrical surface adapted to make a sliding fit within a companion internal cylindrical annular surface, and an electrical connection between said transmitter unit and

said amplifier unit, said transmitter unit being adapted when urged axially away from the amplifier unit to become automatically disconnected therefrom.

17. In transmitter apparatus of the class described, a housing, one side of said housing being open to detachably receive an amplifier unit, a portion of said housing oppositely disposed from said opening being adapted to support a condenser type transmitter, a condenser type transmitter supported by said housing, a frame detachably mounted in said housing adjacent said supported transmitter, a substantially complete amplifier unit carried by said frame, and electrical connections between said transmitter unit and said amplifier unit.

18. In transmitter apparatus of the class described, a housing, a condenser type transmitter supported on one side of said housing, a cover member on the opposite side of said housing which is adapted when open to enable the association within the housing of an amplifier unit, a frame, and a substantially complete amplifier unit carried by said frame, said frame being detachably mounted within the housing between said transmitter unit and said cover member.

19. In transmitter apparatus of the class described, a housing, a support detachably mounted within said housing, amplifier elements such as vacuum tubes carried by said support and movable therewith as a unit, whereby the amplifier elements carried by the support may be readily attached or detached with respect to said housing, and a transmitter unit supported by said housing in juxtaposition with respect to the housed amplifier unit.

20. In transmitter apparatus of the class described, a housing, one side of said housing being open to detachably receive amplifier elements, a portion of said housing oppositely disposed from said opening being adapted to support a condenser type transmitter, a condenser type transmitter supported by said housing, a carrier detachably mounted within said housing adjacent said supported transmitter, amplifier elements mounted on said carrier, and electrical connections between said transmitter unit and said amplifier elements.

In testimony whereof, we have hereunto subscribed our names.

JOHN ELLIOTT JENKINS.
SAMUEL E. ADAIR.
